UNITED STATES PATENT OFFICE.

FRANK FIEBEGER, OF AKRON, OHIO.

DESIGN FOR A STOVE.

SPECIFICATION forming part of Design No. 37,344, dated February 14, 1905.

Application filed January 3, 1905. Serial No. 239,541. Term of patent 14 years.

To all whom it may concern:

Be it known that I, FRANK FIEBEGER, a citizen of the United States, residing at Akron, in the county of Summit and State of Ohio, have invented a new, original, and ornamental Design for Stoves, of which the following is a complete specification, reference being had to the accompanying drawing, forming a part hereof.

The drawing presented represents a perspective of the stove, showing my design.

What I claim, and desire to secure by Letters Patent, is—

The ornamental design for a stove as shown.
FRANK FIEBEGER.
